UNITED STATES PATENT OFFICE.

STEPHEN P. M. TASKER, OF PHILADELPHIA, PENNSYLVANIA, ASSIGNOR TO
JOSEPH R. TASKER, OF SAME PLACE.

BOTTLE-STOPPER.

SPECIFICATION forming part of Letters Patent No. 292,449, dated January 22, 1884.

Application filed July 16, 1883. (No model.)

To all whom it may concern:

Be it known that I, STEPHEN P. M. TASKER, of the city and county of Philadelphia, and State of Pennsylvania, have invented an Automatic Stopper for Bottles, Jars, and kindred containing devices, of which the following is a specification.

My invention relates in general to the class of devices employed for closing the mouths of bottles, jars, or other vessels by means of stoppers connected with bails and adapted to be retained in place against the pressure of the bottle's contents, and relates specifically to the class of stoppers which are connected with the bails and are adapted to be swung laterally off with the bail when the stopper-locking devices have been operated to effectuate the release of the stopper.

A good form of a convenient embodiment of my invention is hereinafter described and claimed.

In the accompanying drawings, Figure 1 represents in side elevation, and Fig. 2 in central vertical sectional elevation, a jar equipped with my improved stopper or cover. Fig. 3 is a perspective detail of one of the stopper-operating bell-crank levers. Figs. 4 and 6 are, respectively, a side elevation and a vertical central section of a bottle embodying my improvements; and Fig. 5 is a top plan view of the same.

Similar letters of reference indicate corresponding parts.

The object of my invention is the provision of a stopper or cover for jars or bottles which is adapted to seat itself on top of the rim, chine, or mouth of the jar or bottle, and which is not only retained tightly thereupon by automatically-operating mechanical devices, but which is also more rigidly seated or tightened in place by the pressure of the vessel's contents, so that the device is especially applicable to vessels or bottles containing effervescent fluids.

Referring first to the first three figures of the drawings, which represent my device as applied to a fruit-jar, A is the body of a jar or kindred vessel, of vitreous or other material, the rim or chine of which is supposed to be trueed off or leveled in a horizontal plane.

B is a bail of strong wire or other suitable material, pivoted to a bail-ring, C, preferably seated in a sunken head, D, formed circumferentially in the jar. The bail is capable of a swinging movement about its pivotal connection with the bail-ring. 55

E is a circular or other shaped diaphragm, of rubber, leather, or other elastic flexible material.

F is a central disk or lever-rest, of metal, wood, glass, or other suitable substance, which is of less diameter than the diameter of the mouth of the vessel; and G is an annular ring, fitted to surround the disk, and preferably composed of metal, although it may be made of other substance. The disk, ring, and diaphragm together constitute the cover or stopper proper of the vessel. 60 65

H is what I term a "stopper-stem," being a bolt or rod of metal, passing, in the arrangement shown, vertically through the diaphragm and disk, so as to connect the two together, and passing up through a hole in the bail or a perforated boss or washer, e, integral with the bail, through a tubular rubber spring or cushion, I, and terminating in a presser button or knob, J, rigidly connected with it and adapted to hold the rubber spring or cushion in place upon the bail. The ring G is preferably, although not necessarily, connected with the flexible diaphragm. 70 75 80

K, K are two bell-crank levers or cams, pivotally connected with or fulcrumed to the bail upon either side of its boss in such position that one arm of each lever rests upon the disk 85 and the other arm of each lever rests upon the ring.

Such being a description of the several members or contrivances together, in their assembled relation composing my device, the operation of the same will be readily understood. The stopper proper being supposed seated upon the mouth of the vessel, in order to unseat it pressure is brought to bear upon the button or knob, so as to compress the rubber spring between said button and the bail, the result of which is that the stem is forced downward, so as to carry down with it the disk and central portion of the flexible diaphragm, a result attended with the dropping of the ex- 90 95 100

tremities of the levers which rest upon the disk, so as to cause the elevation of the opposite extremities thereof which rest upon the ring. In this condition of parts the stopper 5 can be swung with the bail or slipped laterally from the mouth of the vessel. In order to close the vessel the bail is swung until the stopper is concentric with the mouth or in proper position thereupon. Pressure upon the 10 button or knob is then removed, whereupon the rubber spring or cushion expands and forces the button or knob upward away from the bail, with the further result that the stopper-stem, following the button, lifts with it the 15 disk, and causes the latter to exert an upward pressure upon the extremities of the bell-crank levers which rest upon it, so as to cause the deflection of the outer extremities of said levers which rest upon the ring, and the con- 20 sequent exertion of their pressure upon said ring, which in turn presses downwardly upon the diaphragm, and effects a hermetical sealing of the cover proper upon the mouth of the vessel through the compression of the dia- 25 phragm thereupon.

It is obvious that the above result is due to the recoil or expansion of the rubber spring or cushion; but it is also obvious that the pressure of the bottle's contents operating 30 against the flexible diaphragm, and, through the medium of the latter, against the disk, tends to force upward the disk and to exert further pressure upon the levers, so as through them to cause further downward pressure 35 upon the ring, and the exterior or circumferential portion of the diaphragm, which is between the ring and the chine of the vessel.

The result of the pressure of the bottle's contents in this device of mine is different 40 from the same result as produced upon internal stoppers which are forced into a seat within the neck or mouth of a vessel, for the reason that I utilize said pressure, through the instrumentalities described, to firmly seat 45 and retain seated an external stopper or cover as opposed to one within the vessel.

In Figs. 4, 5, and 6 I have represented my devices as applied to an ordinary bottle, and, as will be readily observed by comparison of 50 the two sheets, the construction and arrangement of the device is practically identical. The bail-ring is shown seated below the bead of the neck of the bottle as opposed to being seated in a sunken bead upon the body of the 55 jar. I have also represented a spiral spring between the button and bail instead of a rub-

ber cushion. I have in addition shown the inner ends of the bell-crank levers as weighted. These several changes, however, are merely mechanical.

60

It will of course be understood that the details of construction and application of the bail and bell-crank levers and the various parts composing the cover proper can be varied without departure from the invention 65 strictly as such. Thus the levers may be made in the form of pivoted cams, and the diaphragm need not be secured to the stem.

It is obvious that my device is self tightening, not only by virtue of the expansion of 70 the spring, but by the pressure of the vessel's contents when of such character as to generate pressure.

It is also obvious that while the most convenient and best form of the contrivance upon 75 which the inner extremities of the levers rest is that of a disk, as represented and described, it is perfectly competent for me to vary the form of the disk and to use instead simply a diametric bar, plate, or kindred contrivance 80 upon which the inner extremities of the levers can rest, and which will tend to transmit the movement imparted to the stem to which they are connected to the inner extremities of 85 said levers.

Having thus described my invention, I claim—

As an improvement in stoppers or covers for bottles, jars, and other vessels, the combination, with a bail secured to the vessel, of a 90 cover composed of a flexible diaphragm, a ring resting thereon, a disk or rest for the inner arms of the levers, a stem connected with the disk and provided with a head or pressure knob, a spring or cushion interposed between the bail and the pressure-knob of the 95 stem, and bell-crank levers or cams pivoted to the bail, and resting as to their inner extremities upon the disk, and as to their outer extremities upon the ring, the construction being 100 such that the cover as an entirety is seated externally upon the neck of a bottle or vessel, and is held in place thereon by the expansion of the spring and the pressure of the bottle's 105 contents, substantially as set forth.

In testimony whereof I have hereunto signed my name this 30th day of June, A. D. 1883.

STEPHEN P. M. TASKER.

In presence of—

J. BONSALL TAYLOR,
JOHN JOLLEY, Jr.
